UNITED STATES PATENT OFFICE.

GEORGE S. NORRIS, OF BALTIMORE, MARYLAND.

BOTTLE-STOPPING DEVICE.

SPECIFICATION forming part of Letters Patent No. 293,269, dated February 12, 1884.

Application filed November 9, 1883. (No model.)

To all whom it may concern:

Be it known that I, GEORGE S. NORRIS, a citizen of the United States, residing at Baltimore, in the county of Baltimore and State 5 of Maryland, have invented certain new and useful Improvements in Bottle-Stopping Devices, of which the following is a specification, reference being had therein to the accompanying drawings, in which—

10 Figure 1 is a perspective view of my improvement applied to the neck of a bottle closed thereby. Fig. 2 is a vertical section of the same, showing the mouth of the bottle open. Fig. 3 is a perspective view of the 15 sheet-metal cap turned upside down to show the inner disk cut therefrom. Fig. 4 is a perspective view showing a modification of the sheet-metal cap. Fig. 5 is a perspective view of the rubber plug. Fig. 6 is a vertical section of the rubber plug constructed according 20 to my invention and secured to a cast-metal cap. Figs. 7 and 8 are perspective views of the neck-band and a modification thereof.

My invention relates to bottle-stopping devices in which a rubber plug is compressed over and within the mouth of a bottle by means 25 of a combined stopper cap and bail adapted to be connected at one end, by means of a link and a hinged lever, to a band secured to the 30 neck of said bottle, and to the other end by means of a link pivoted to the coiled or looped portion of said band, and is an improvement 35 upon the construction of the stopper, cap, and rubber plug shown in my Patent No. 272,081, of 13th February, 1883; and the objects of my 40 improvements are, first, to provide the stopper with a cap that can be struck out of sheet metal, and have its rim rest uniformly upon the stopper-plug when locked thereon while 45 the bottle is closed; and, second, to give such a form to the cavity within the plug as to cause it to expand laterally within the bottle-mouth when the bottom of said cavity is subjected to vertical pressure, and also cause the stopper 50 to jump clear over and to one side of the bottle, and thereby release the stopper-plug of all compression and allow it to resume its primitive form while the bottle is open. I attain these objects by the construction illustrated in the accompanying drawings, in which—

A represents the neck of the bottle, and B the rubber plug. It is made with a collar, B', to rest upon the edge of the bottle-mouth, and has a hole, b', in its top surface, eccentrically to the center thereof, as shown in Figs. 2 and 55 5, and concentrically, as shown in Fig. 6, leading into a circular cavity in the center of the plug. To connect the plug with the stopper-fastenings and furnish it with a support having some degree of elasticity to press against 60 the floor of the center cavity, the cap D is used. This cap is stamped out of sheet metal, and is circular, with two lugs, d, projecting diametrically from the periphery thereof, and out of the center is cut a disk, d', having an arm, d'', 65 that connects it permanently with the body of the cap. After the cap's blank has been stamped or cut out of a flat sheet of metal, the arm d'' is bent downwardly at the point where it is united to the cap, and horizontally again 70 at the point where it joins the disk d', so that said disk will occupy a position parallel with the bottom surface of the cap, and about three-sixteenths of an inch therefrom. The disk d' and arm d'' are thus in position, after having 75 been inserted within the plug B, to press against the floor of the cavity b, upon a central elevation, b'', projecting from its interior surface, to partly distend it downwardly and laterally when forcing the plug within the 80 bottle-mouth. While releasing the bottle of its fastenings this downward distention of the bottom of the rubber plug has, by its resilience, a tendency to throw the cap D upward, and the latter carries the plug in its flight clear 85 off the bottle-mouth. With this object in view the thickness of the upper portion, b', of the plug covering its cavity is only about one-eighth of an inch, and consequently less than the length of the arm d'', carrying the disk d' of 90 the cap-plate. The rectangular opening b' in the top of the plug is of such size as to easily receive the disk d' of the cap. The disk or button of the cap-plate may be stamped out of said plate in two halves, each having a stem, 95 as shown in Fig. 4. The lugs d, projecting from the edge of the cap, are bent under to form eyes to receive the links f and f', that unite the cap to the neck-band E. The latter is made of a piece of wire bent first upon itself at e' in the 100

middle of its length, and that part coiled to form an eye or bearing, e^4 , of suitable length to receive and keep steady a portion of the link f , and each branch of the wire forming the neck-band is bent in a semicircle to fit the neck of a bottle, and furthermore bent outwardly to form a bearing for the link f' , and again bent inwardly to form a journal for the locking-lever G . The construction and operation of this lever, having been fully described in my Patent No. 272,081, will not require now any further description.

The rubber plug B , having the central elevation, b^2 , projecting from the floor of its cavity, can be used in connection with a cast-metal cap, D' , having a central stem and button, d^5 , and substantially the same results be obtained, as said button will press upon the elevation b^3 of the rubber plug and diffuse or spread it downwardly and laterally against the interior of the neck of the bottle in the act of closing it.

Having now fully described my invention, I claim—

1. A bottle-stopper cap consisting of a sheet-metal plate having two peripheral lugs, a disk, 25 and an arm carrying said disk, stamped from said plate, substantially as and for the purpose described.

2. The combination of a bottle-stopper cap with a rubber plug having a central cavity, 30 the floor of which cavity has a central projection resting against the end of the device forming a part of the stopper-cap, substantially as and for the purpose described.

3. The combination of a bottle-stopper cap 35 with a rubber plug having a central cavity and an opening, d' , in the top surface of said plug, leading into the side of said cavity, or eccentrically to said top, substantially as described.

In testimony whereof I affix my signature in presence of two witnesses:

GEORGE S. NORRIS.
